UNITED STATES PATENT OFFICE.

JOSEPH WUEST AND FREDERICK LUDWIG, OF CINCINNATI, OHIO, ASSIGNEES TO THE HEEKIN CAN COMPANY, OF CINCINNATI, OHIO, A CORPORATION OF OHIO.

VESSEL CLOSURE.

Application filed February 4, 1925. Serial No. 6,818.

Certain products generally packed in containers such as pails and buckets, must from their nature, be sealed against the atmosphere. One such product is a lard substitute comprising homogenized vegetable fats. It has been the practice to dispense such products in sealed pails and the ultimate consumer would cut out the lid of the container with a can opener or the like, wherefore the container, because of such mutilation and because of the resultant sharp edges left on the container, could not be utilized except with extreme care and only at such great risk of physical injury that generally 10 such containers were thrown away. These containers, if they were usable, were very desirable to the poorer classes, yet, for the reasons stated, the use thereof was generally dispensed with.

20 An object of our invention is to provide means for sealing a smooth edged vessel or container, so that after the seal is broken and the container is emptied, the container may be used for the same purposes for 25 which similar unsealed containers are used.

Another object of our invention is to provide simple and efficient means for accomplishing the purpose stated.

Another object is to provide a means for 30 the purpose stated that is economical of production and application.

Another object is to provide means that may be readily detached from the container without the employment of special 35 instruments and without mutilating the container.

Another object of our invention is to provide a device wherein the likelihood of injury to one opening the container is reduced 40 to a minimum.

These and other objects are attained by the means described herein and disclosed in the accompanying drawings, in which:

Fig. 1 is a side elevation of a pail having 45 mounted on it a lid or closure together with sealing means, all of which form details of our invention.

Fig. 2 is a plan view of the device shown in Fig. 1.

50 Fig. 3 is an enlarged fragmental sectional view on line 3—3 of Fig. 2.

Fig. 4 is an enlarged fragmental view of the disclosure in Fig. 3.

55 Fig. 5 is a plan view of a lid forming a detail of our invention.

Fig. 6 is an enlarged sectional view on line 6—6 of Fig. 5.

Figs. 7, 8, 9 and 10 are plan views similar to Fig. 2 and showing the steps incident to removal of a lid and sealing ring from a 60 pail such as is shown in Fig. 1.

The pail 20 is provided at its upper end with an outwardly turned bead 21, whereby to provide a smooth unobstructed inner surface 22 of the pail affording no inaccessible 65 crevice or the like in which anything may lodge and therefore permitting ready and easy cleansing of the inside of the pail. A lid 23 provided with an annular U-shaped groove or ledge 24, is adapted to close the 70 mouth of the pail, the groove assuming an inverted position and adapted to receive the bead 21. Preferably the groove carries a sealing compound 25, for example, a solution of benzol and rubber, or latex or sap 75 of rubber tree dissolved in aqua ammonia, that will, in co-operation with the walls of the groove and bead, form an air tight seal. A locking ring 26, open at its center, has formed in it an annular U-shaped groove 80

27 for receiving the bead 21 and ledge 24, and the annular edge of the lid 23. The outer annular edge 28 of the sealing rim is adapted to be lodged under the bead 21 for 85 securely clamping the sealing ring and the lid upon the bead 21. The lid and locking ring are applied under pressure. The locking ring comprises a radially extending tearing tab 29 provided with an aperture 30. At opposite sides of the tearing tab 90 29 the locking ring is cut away to provide inwardly diverging slots 31 and 32. The outer edges of the slots 31 and 32 are disposed adjacent the upwardly formed bead 33 of the locking ring, the inner face of 95 which bead defines the groove 27 in the locking ring. The inner annular edge 34 of the locking ring is bent slightly in relation to the intermediate portion or body 35 of the locking ring so that an annular flange 100 is provided that yieldingly engages upon the upper face 36 of the lid 23, the engagement being at the extreme inner edge of the annular flange and entirely around the flange, the contact between the flange and 105 the lid being annular.

It is readily apparent by reference to Figs. 3 and 4 that the application of the lid and locking ring to the pail, under pressure, serves to seat and retain the sealing 110

compound between the ring and the pail so as to seal the contents thereof.

When the pail is to be opened, an ice pick or the like 37 has its point inserted 5 through the aperture 30, see Fig. 7. The ice pick is projected through the opening, until the point thereof may be brought into engagement upon the locking ring at some distance from the tab 29, for example as 10 shown in Fig. 8. In order to accomplish this, the ice pick should be inserted from the outside as shown in Fig. 7, and the tab should be twisted upwardly as disclosed in 15 Figs. 8 and 9. When the point of the ice pick rests upon the sealing ring as shown in Fig. 2, the handle is lifted thereby transversely tearing the sealing ring as disclosed in Fig. 9. The weakening of the sealing ring by provision of the inwardly diverging slots 31 and 32 assures a transverse 20 tearing of the tab so that after the ring has been torn or severed as shown in Fig. 10, the locking ring may be completely removed from the pail. Occasionally the 25 tearing tab may be torn completely off of the pail. Should this happen, it is necessary only that the point of the ice pick be inserted into the opening or crevice 38 formed at the edge of the locking ring and between 30 the bead 21, annular ledge 39 of the lid, and the outer edge 28 of the locking ring, see Fig. 4, for effecting unseating of the locking ring annularly of the pail. The point of 35 the pick may be utilized for unseating the lid by bringing same to bear upon the outer

annular edge of the lid at the junction thereof with the bead on the pail. Pressure directed upon the lid at the said point will effectively and expeditiously loosen the lid from the pail.

It will be noted that the engagement of the yielding flange of the ring on the top or lid precludes injury that occasional raw edges on the ring might inflict on persons who may handle the pail.

What we claim is:

1. The combination with a can having a lid beaded to the rim of the can and having an annular depression adjacent said bead, of a sheet-metal sealing-ring having its outer edge beaded over the lid-bead and its inner resilient portion extending across said depression and having its extreme circular edge bearing down resiliently on the top face of the lid.

2. The combination with a can having a lid beaded to the rim of said can, of a sealing-ring having its outer edge beaded over the lid-bead and its inner circular part extended inwardly to form an annular flange bearing down on the top face of the lid, the edge of said flange being provided with spaced notches forming between them a tab, said notches terminating short of the aforesaid bead.

In testimony whereof, we have hereunto subscribed our names this 30th day of January, 1925.

JOSEPH WUEST.
FREDERICK LUDWIG.
